CIGARETTENMASCHINEN-FABRIK, J. C. MÜLLER & CO.

MEANS FOR DELIVERING AND SORTING CIGARETTES FROM CIGARETTE-MAKING
MACHINES.

Application filed March 31, 1924. Serial No. 703,303.

To all whom it may concern:

Be it known that I, LOUIS PAUL GRAUPNER, a subject of the Republic of Germany, residing at Pennricherstrasse 23, Dresden-
A, Germany, have invented certain new and useful Improvements in Means for Delivering and Sorting Cigarettes from Cigarette-Making Machines, of which the following is a specification.

- 10 In the more recent exceedingly high speed rod or rope-forming cigarette machines the cigarettes leaving their groove and already separated from the rod are not released with sufficient reliability from the rod if left to themselves to fall freely and be led away by inclined faces, feed drums or the like to the delivery outlet. This drawback is not overcome by allowing the cigarettes to drop into receiving pockets or the like arranged 20 on an endless band or the like moving in the direction of the rod with a speed which is greater than the speed of the rod. As a result the cigarettes are entrained by friction but this friction according to experience is not sufficient to ensure the release of the cigarettes from the rod at high speeds of the rod. The cigarettes therefore must be positively seized and led away by clamping jaws or the like.
- 25 The present invention consists in the arrangement at regular intervals apart on the periphery of a disc-like continuously rotating carrier (the peripheral speed of which exceeds the speed of the rod) of pairs of positively actuated clamping jaws in such manner that each cigarette leaving the groove is gripped by a pair of clamping jaws as they are closing, which is entrained therewith and led to a sliding surface over 30 which the pair of clamping jaws open and release the cigarette, two successive sliding surfaces being provided and the control of the clamping jaws being such that the cigarettes carried thereby are alternately deposited on the first, and then on the second sliding surface.
- 35 The new device is illustrated in the accompanying drawing in Fig. 1 in side ele-

vation and in Fig. 2 in vertical section on the line 2—2 of Fig. 1.

Referring to the drawing, on a shaft 2 fitted with a driving bevel pinion which is mounted in bearings 3 on the machine frame is secured a disc 4 which rotates continuously with the shaft 2.

On the periphery of this disc at regular intervals apart are pivotally mounted pairs of opposed bell crank levers 5 adapted to pivot about the pivots 6 carried by the disc. The ends 7 of these bell crank levers 60 projecting over the edge of the disc wheel carry opposed clamping jaws 8 which are preferably of resilient material such as rubber or the like.

On each bearing 3 concentrically of the shaft 2 is mounted a cam disc 9 i. e., on both sides of the carrier disc 4 is located a cam disc. Each cam disc has two cam faces 10 and 11 axially disposed with respect to one another. The pairs of clamping jaws are 70 divided into two groups. The one group consisting of the first, third and fifth pair of clamping jaws is actuated by the cam 10 and the second group consisting of the second, fourth, and sixth pairs of clamping 75 jaws is actuated by the cam 11.

On the free ends of the bell crank levers 5 are fitted rollers 12 which by means of springs 13 are pressed on the periphery of the cam faces 10 or 11. The cam faces are 80 so arranged that on rotation of the carrier disc 4 each pair of clamping jaws is closed by the movement of the bell crank lever 12 at the moment when the cigarette Z is projected sufficiently far from the groove A 85 and rests on the periphery of the disc 4. As the disc rotates with a peripheral speed exceeding the speed of the cigarette rod the cigarette gripped by the clamping jaws is released from the rod with certainty. It 90 is entrained by the jaws and released when over an inclined surface 14, if the pair of jaws is actuated by the outer cam faces 11 the drop in the cam groove at 15 causing the separation of the clamping jaws 8. The inclined surface 14 is disposed tangentially of

the disc 4 in such manner that the cigarette entrained by the clamping jaws may pass straight through the slit between the outer end and the edge of the disc 4. When now 5 the clamping jaws are separated the cigarette is dropped on the inclined surface disposed directly beneath the pair of clamping jaws the acceleration ensuring the downward movement over the inclined surface. 10 This inclined surface inclines also slightly to one side so that the cigarette will roll down transversely of the plane of the disc on to the endless band 16.

When the cigarette, however, is gripped 15 by a pair of clamping jaws actuated by the inner cam faces 10 the clamping jaws are opened when the depression 17 in the cam 10 is reached so that this cigarette drops on 20 the second inclined surface 18 located behind the first inclined surface and also disposed tangentially of the periphery of the disc 4. This second inclined face is also inclined slightly to one side so that the cigarette will roll down thereon transversely 25 of the disc on to the endless band 16.

As the pair of clamping jaws are alternately opened at 15 and 17 the cigarettes are deposited on the band 16 in two positions in such manner that only those cigarettes 30 having similarly directed mouth piece ends arrive at each delivery outlet.

As the high speed rod-forming cigarette machines deliver so many cigarettes at the two outlets that the workers at each delivery 35 outlet are unable to remove the cigarettes as they arrive there may be provided with the new device four delivery outlets.

Having now particularly described and ascertained the nature of my said invention 40 and in what manner the same is to be performed, I declare that what I claim is:—

1. A device for delivering cigarettes from a rod forming cigarette machine, comprising a continuously revolving body, means on 45 and revolving with said body capable of periodically gripping a cigarette when brought into the path of the cigarette rod, a sliding surface in close proximity to the periphery of said body and means for causing the release of the cigarette from said gripping means the instant it arrives close to said sliding surface.

2. A device for delivering cigarettes from a rod forming cigarette machine, comprising 55 a continuously revolving body having a peripheral speed exceeding that of the cigarette rod, means on said body capable of periodically gripping a cigarette when brought into the path of the cigarette rod, an inclined surface in close proximity and tangential to the periphery of said body and means for causing the release of the cigarette from said gripping means the instant it arrives close to said inclined surface.

3. A device for delivering cigarettes from a rod forming cigarette machine, comprising 65 a continuously revolving body, pairs of gripping jaws carried by said body, means for closing said jaws to grip a cigarette when brought into the path of the cigarette rod, 70 a sliding surface in close proximity and tangential to the periphery of said body and means for opening said jaws to release the cigarette the instant it arrives close to said 75 sliding surface.

4. A device for delivering cigarettes from a rod forming cigarette machine, comprising a continuously revolving body, cam controlled 80 pairs of gripping jaws carried by said body and adapted to close and grip a cigarette when brought into the path of the cigarette rod, and an inclined surface in close proximity to said body, said jaws being adapted to open and release the cigarette the instant 85 it arrives close to said surface.

5. A device for delivering and sorting cigarettes from a rod forming cigarette machine, comprising a revolving body, two sets of pairs of gripping jaws carried by said 90 body, cams adapted to alternately control the operation of said two sets of jaws and two inclined surfaces arranged in close proximity to the periphery of said body, said sets of jaws being adapted to alternately close and grip cigarettes when brought 95 into the path of the cigarette rod and to open and release the cigarettes, when arriving close to said inclined surfaces.

6. A device for delivering cigarettes from a rod forming cigarette machine, comprising 100 a plurality of cam controlled jaws adapted to revolve with a speed exceeding that of the cigarette rod and to close and grip a cigarette when coming into the path of the cigarette rod, and a cigarette receiving means arranged in proximity to the circular path of said jaws, said jaws being adapted to open and release the cigarette the instant 105 they arrive close to said receiving means.

7. In a device for delivering and sorting cigarettes from a rod forming cigarette machine, a revolving body, a plurality of radially projecting gripping means on said body, said means comprising two sets of spring 115 actuated pivoted pairs of jaws, stationary cams alternately controlling the operation of said sets of jaws, so as to cause them to alternately close and grip the cigarettes when coming into the path of the cigarette rod and receiving surfaces tangential and in proximity to the periphery of said body, said cams causing the opening and release of said cigarettes when said jaws arrive close to said surfaces.

8. In a device for delivering and sorting cigarettes from a rod forming cigarette machine, a revolving body, a plurality of gripping jaws thereon adapted to grip a ciga- 120-125

rette when coming into the path of the cigarette rod, a cigarette receiving surface arranged about tangentially and in proximity to the periphery of said body and inclined 5 relatively to the horizontal plane both longitudinally and transversely, and a conveyor below said surface, said jaws being adapted to open and release a cigarette the instant the same arrives close to said surface, the

latter causing the cigarette to slide down 10 longitudinally and roll in a transverse direction onto the said conveyor.

In testimony whereof I affix my signature in presence of two witnesses.

LOUIS PAUL GRAUPNER.
